(57) **CLAIM**

The ornamental design for a beverage container, as shown and described.

DESCRIPTION

FIG. 1 is a top perspective view of a beverage container of the present invention;

FIG. 2 is a bottom perspective view of the beverage container of the present invention;

FIG. 3 is a left side elevation view of the beverage container of the present invention;

FIG. 4 is a right side elevation view of the beverage container of the present invention;

FIG. 5 is a front elevation view of the beverage container of the present invention;

FIG. 6 is a rear elevation view of the beverage container of the present invention;

FIG. 7 is a top plan view of the beverage container of the present invention; and,

FIG. 8 is a bottom plan view of the beverage container of the present invention.

The broken lines showing of the cap, bottom features, and depression in the rear of the base in all figures are for illustrative purposes only and form no part of the claimed design. The outermost circle of the unclaimed patterned punt and the notched area shown in broken lines on the bottom of the beverage container, which define the bounds of the claimed design, form no part thereof.
